TELEPHONE REPEATER

Leonard G. Abraham, Madison, and Doren Mitchell, Bound Brook, N. J., assignors to American Telephone and Telegraph Company, a corporation of New York

Application September 1, 1933, Serial No. 687,880

6 Claims. (Cl. 179—170)

This invention relates to telephone repeaters, and more particularly to two-way repeaters for use with irregular two-wire telephone lines.

It is the object of the invention to provide a type of repeater that can be used with lines of such a degree of irregularity in construction as to preclude the use of ordinary types of repeater with more than a very low gain. A second object of the invention is to obtain a substantial gain from such a repeater, while introducing a minimum of distortion or other disturbance in the telephone circuit.

A further object of the invention is to provide means for preventing noise which may exist on the telephone circuit from interfering with the obtaining of the desired results from the repeater.

It is well known that with the type of telephone repeater ordinarily used with a two-wire line, the amount of gain that can be obtained is limited by the similarity between the impedances of the lines in the two directions and those of the artificial lines or networks that are used to balance them. The measure of this similarity is called the "return loss" between the line and its network. This similarity in turn depends largely upon the uniformity or regularity with which the lines are constructed, since, while it is usually possible to construct a simple network whose impedance is similar to that of a line of uniformly distributed or regularly recurring constants, it is usually not possible to construct at reasonable cost a similar network for an irregular line. This is particularly true of a loaded line. If the loading coils are of equal inductance and equally spaced, and the capacity of the line itself is uniform, little difficulty is encountered in constructing a simple network whose impedance characteristic is similar to that of the line, within the frequency range that is of interest. If there are serious irregularities in inductance or capacity, however, or in the spacing of the coils, the impedance characteristic of the line is so irregular that it is impossible to simulate it with any reasonable type of network.

It is usual, therefore, to make every effort to secure a high degree of uniformity in constructing a line with which repeaters are to be used. Sometimes, however, this is impossible to attain; or it may become necessary to use repeaters on a line which had previously been constructed without thought of such use. Under these circumstances the impedance of the line may be so irregular as to make it impossible to obtain the desired gain from the repeater. Again, it may be desirable to switch a repeater to any one of

several lines of different impedances. In such a case it would be necessary to use a network whose impedance was a compromise between those of the various lines, and it would not be possible to obtain a high singing point against any of them. It is such conditions as these that can be taken care of by our invention.

The effect of impedance dissimilarity or low return loss between the lines and their respective networks is to cause circulating currents to flow within the repeater, thus interfering with its action in amplifying telephonic currents arriving from the lines. We propose to insert in the path of these circulating currents sufficient attenuation to reduce them to negligible proportions, and to provide voice-operated devices, actuated by the telephonic currents arriving from the lines, to divide the attenuation unequally between the two sides of the repeater. Thus when telephonic currents reach the repeater, for example, from the west line, the major part of the attenuation will be inserted in the side of the repeater transmitting from east to west, so that the telephonic currents passing through from west to east will receive a net amplification.

The invention will be clearly understood when the following description is read with reference to the accompanying drawings. In the drawings, Figure 1 shows one embodiment of the invention in its simpler form, while Fig. 2 shows the invention in a somewhat more complex arrangement which is deemed preferable in certain circumstances. Similar reference characters designate similar parts of the circuit in the two figures of the drawings.

In each figure of the drawings, A and A' indicate the telephone lines in the two directions, and B and B' the artificial lines intended to balance them. C and C' are balanced or hybrid coils or transformers as ordinarily used in two-wire repeaters, and D and D' are the amplifier circuits for the two directions of transmission. Thus, B, C, D and B', C', and D', as connected by the heavy lines J, J' and K, K' in the drawings, constitute the essential parts of a well-known form of two-wire telephone repeater.

With this type of repeater, voice currents arriving over the line A are amplified in D and delivered to coil C'. If line A' and network B' are approximately equal in impedance, the amplified voice power will divide approximately equally between them, and only a small portion of it will pass through to conductors J' and enter amplifier D'. The portion of the power which thus passes through the coil from K to J' is a

function of the return loss between A' and B'. The power entering amplifier D' will be amplified and delivered to coil C, and a portion of it, determined by the return loss between A and B, will reach conductors J and be amplified again by D. If the sum of the two amplifications in D and D' is greater than the sum of the two losses in passing through coils C and C', a circulating current will be sustained through the repeater, and it will become practically inoperative for transmitting conversation.

To avoid this condition, and permit a reasonable gain to be obtained even when the return loss is low, we propose to insert losses in the path of the circulating currents, which losses are under the control of the voice currents themselves. These losses are designated in Fig. 1 by H and H': they are indicated as simple shunt resistances, but it will be understood that they may take a variety of forms, and that their position in the circuit may be changed, without departing from the spirit of the invention. Either of these losses is sufficient by itself to prevent a condition of sustained singing. The losses are connected to the circuit through the contacts of the relays G, G', which are normally not operated, since the circuits through their windings are broken by the normally open contacts of the relays F, F'.

Relays F and F' are in the output circuits of a pair of amplifier-detectors E and E', of any well-known type. The inputs of these amplifier-detectors are bridged across the conductors J and J', respectively, in parallel with the inputs of the repeater amplifiers D and D'. They are therefore affected by incoming speech currents from the lines A and A', respectively.

Considering the effect of speech currents arriving from line A, it will be seen that a portion of them will enter amplifier-detector E, and if of sufficient magnitude will cause relay F to operate. The upper contact of this relay closes the circuit through the winding of relay G, which removes loss H from the transmission circuit, thus permitting the gain of amplifier D to be effective. The lower contact of relay F breaks the circuit from amplifier-detector E' to relay F', thus making it impossible for relay F' to operate, and ensuring that loss H' remains in the path of the circulating currents to prevent singing. It is essential that either H or H' shall be in the singing path at all times.

When speech currents cease to arrive from line A, relay F releases, breaking the circuit through relay G, and restoring the connection between E' and F'. Loss H is thus reinserted, and both amplifier-detectors are in a position to function. Relays F and F' may be arranged for slow release, so that they will not drop back between syllables or between words, but only during definite pauses in the speech.

On the arrival of speech currents over line A', an exactly analogous operation takes place through amplifier-detector E' and relays F' and G'. Loss H' is removed from the circuit, and amplification is provided for the speech from A' towards A. Operation of relay F' is prevented by the open contact of F', and loss H is maintained in the singing path. Each direction of conversation thus receives amplification, in spite of low return losses.

If speech currents arriving from either line are too weak to operate the relays, losses will remain in the circuit, and such currents will not receive the desired amplification. They will not be lost altogether, however, since losses H and H' will

be made only just large enough to provide a suitable margin of safety against singing, and against the distortion which results from a near approach to singing. It may even be possible to obtain some amplification, if the return losses are not too low.

The simple circuit of Fig. 1 is, under certain conditions, open to a number of objections. We therefore prefer the circuit of Fig. 2, which accomplishes essentially the same result, but in an improved manner.

One of the important objections to the circuit of Fig. 1 is that each of the losses H, H' must be great enough in itself to provide a suitable margin against singing. In the normal or unoperated position of the relays, both losses are in the circuit, giving a much greater margin than necessary. Weak speech, and the initial sounds of speech before the relays have time to operate, will therefore be attenuated approximately twice as much as is needful. In the preferred circuit of Fig. 2 we have avoided this effect by dividing each loss into two parts, H₁, H₂, H'₁ and H'₂, respectively, controlled by the relays G₁, G₂, G'₁ and G'₂. Any two of these losses are sufficient to give the desired margin against singing. In the normal position of the relays, H₂ and H'₂ are in the circuit, and H₁ and H'₁ are disconnected. Thus weak speech in either direction suffers only half the loss imposed by the arrangement of Fig. 1. On the arrival of speech from line A, loss H₂ is removed from the circuit, and loss H'₁ is simultaneously inserted in the other side, thus maintaining the singing margin, but obtaining the full gain of the amplifier D in the direction of speech. Similarly, the arrival of speech from line A', with the relays in the normal position, will remove loss H'₂ and insert loss H₁. The manner of accomplishing this will appear from a detailed description of the operation of the circuit.

With both relays F and F' normal, their contacts serve to short-circuit the windings of relays G₁, G₂ and L, and G'₁, G'₂ and L', respectively. On the arrival of speech power from line A, rectified current from amplifier-detector E will operate relay F. This same current will pass through a biasing winding M' on relay F', the direction of this winding being such as to oppose the operation of relay F'. The purpose of this is to prevent false operation of this relay by speech currents arriving from line A, being amplified by amplifier D, and passing through coil C' and on over J' by reason of the unbalance between line A' and its network B'. Such false operation might occur with the simple circuit of Fig. 1. As soon as relay F operates, current will flow from battery Q, through contact P' of relay L', through resistance R, and since the ground through the contact of relay F has been removed, through the windings of relays G₂, L and G₁. Relay G₂ removes loss H₂; relay G₁ inserts loss H'₁; the opening of contact P of relay L disables the relay chain in the opposite direction by disconnecting battery Q'; and the closing of contact N of relay L short-circuits the biasing winding M on relay F, so that voice currents passing through coil C' and acting on amplifier-detector E' cannot cause relay F to release. Thus the speech from line A will be amplified while singing is prevented by the losses H'₁ and H'₂, and operation in the other direction is prevented as long as speech currents are arriving from A.

When speech from that direction ceases, relays

F, G₁, G₂ and L will release after a short interval determined by their construction. H₁' will then be removed from the circuit and H₂ inserted, and the device will be ready to operate on speech from either direction. On speech currents from line A' the action is exactly analogous, loss H₁ being inserted by relay G₁', loss H₂' being removed by relay G₂', the other relay chain being disabled by the removal of battery Q through contact P' of relay L', and biasing winding M' of relay F' being short-circuited by contact N' of relay L'.

There is one difficulty that may at times be encountered in the operation of the device as described to this point. It is desirable to make the relays and the amplifier-detectors quite sensitive, in order to assure as far as possible that weak speech will be able to operate the relays and obtain the gain of the repeater. Weak speech, of course, particularly needs the amplification. On the other hand, with this high sensitivity, there may be noise currents, either induced in the line or picked up by the subscribers' transmitters, which will be of sufficient magnitude to cause the relays to operate. If the noise arrives steadily from one direction, the device will remain operated in that direction, and it will be impossible for speech currents from the other direction to obtain amplification.

To avoid this effect, where necessary, there may be added to the arrangement already described a device for automatically reducing the sensitivity of the relays when noise is present. This device is essentially the same as that disclosed in U. S. Patent No. 1,772,551, granted to D. Mitchell and H. C. Silent. It consists of an auxiliary amplifier-detector circuit, designed to be particularly sensitive to alternating currents of approximately constant intensity, such as would be caused by steady noise, but much less sensitive to currents whose intensity varies rapidly through a wide range, like those caused by speech. The output of the amplifier-detector is used to provide an additional bias opposing operation of the relays, thus reducing their sensitivity in the presence of noise to a point where the noise is incapable of operating them. This reduced sensitivity will, of course, result in loss of amplification on an increased percentage of the speech currents; but this is probably less objectionable than the possibility of locking up the circuit due to noise. The full sensitivity will be obtained when no noise is present.

In Fig. 2, S designates the amplifier-detector circuit, substantially as described in the patent already referred to. It is connected to the circuit through a hybrid coil T, similar to C and C'. The two branches of the hybrid coil are connected to the conductors J and J', in parallel with the inputs of amplifier-detectors E and E', respectively, through hybrid coils W and W'. U is a resistance so proportioned to the input impedance of the amplifier-detector S that there is substantially no transmission through the coil T from J to J' or vice versa, approximately half of any power from either J or J' being dissipated in U, and the balance entering S. A portion, therefore, of any speech or noise currents reaching the repeater from either A or A' will enter the amplifier-detector S. Speech currents will produce comparatively little effect, since as already explained, the circuit is designed to be relatively insensitive to them. Noise currents, however, will produce a direct current in the output circuit of S, the magnitude of this output current depending on the intensity of the noise.

The output current passes through the auxiliary biasing windings V and V' in series, the directions of these windings being such as to oppose the operation of the respective relays F and F'. The proportioning of the circuit is such that this bias is sufficient to prevent the operation of the relays due to steady noise. They will still operate on the more intense portions of speech currents, though with reduced sensitivity. This operation is substantially the same as that described in the patent already referred to, in connection with echo suppressors.

The purpose of hybrid coils W and W' is to prevent the insertion of losses H₁ or H₁' from reducing the input to the desensitizing circuit S. If this occurred when noise was present the bias current in windings V and V' would drop almost immediately and when the noise was removed the noise would then be able to operate relay F or F', as the case might be, for an appreciable interval until the bias current built up again. This would result in objectionable mutilation of speech.

The networks X and X' are of approximately the same impedance as that of the lines J₁ and J₁', respectively. This means that when energy from line A is reaching coil T a change in impedance in line J₂ has very little effect on this energy. The same is true of energy passing from line A' to coil T.

While the invention has been disclosed in specific embodiment for the purpose of illustration, it is to be understood that it may be embodied in other and different forms without a departure from the spirit of the invention, which is defined in the appended claims.

What is claimed is:

1. In a telephone repeater for use with two-wire telephone lines, two separate amplifying elements with variable gain for transmission in the two directions, a voice-operated device associated with each amplifying element, a relay controlled thereby, each relay being adapted to increase the gain of the associated amplifying element and to make a corresponding decrease in the gain of the other amplifying element, and means controlled by each voice-operated device for reducing the sensitivity of the relay controlled by the other voice-operated device.

2. In a telephone repeater for use with two-wire telephone lines, two separate amplifying elements with variable gain for transmission in the two directions, a voice-operated device associated with each amplifying element, a relay controlled thereby, each relay being adapted to increase the gain of the associated amplifying element and to make a corresponding decrease in the gain of the other amplifying element, means controlled by each voice-operated device for reducing the sensitivity of the relay controlled by the other voice-operated device, and means for preventing circulating currents from in turn reducing the sensitivity of either of the relays once it has operated.

3. In a telephone repeater for use with two-wire telephone lines, two separate amplifying elements with variable gain for transmission in the two directions, a voice-operated device associated with each amplifying element, and a relay system controlled by each voice-operated device, each relay system being adapted to increase the gain of the associated amplifying element, to make a corresponding decrease in the gain of the other amplifying element, and to prevent the operation of the other relay system, the repeater

being at all times operative to conduct current in each direction to an appreciable extent.

4. In a telephone repeater for use with two-wire telephone lines, two separate amplifying elements with variable gain for transmission in the two directions, a voice-operated device associated with each amplifying element, a relay controlled thereby, each relay being adapted to increase the gain of the associated amplifying element and to make a corresponding decrease in the gain of the other amplifying element, and means responsive to noise in either side of the circuit for biasing both the said relays to prevent operation thereof by the noise, the repeater being at all times operative to conduct current in each direction to an appreciable extent.
5. In a telephone repeater for use with two-wire telephone lines, two separate amplifying elements with variable gain for transmission in the two directions, a voice-operated device associated with each amplifying element, a relay controlled thereby, each relay being adapted to increase the gain of the associated amplifying element and to make a corresponding decrease in the gain of the other amplifying element, means responsive to noise in either side of the

circuit for biasing both the said relays to prevent operation thereof by the noise, and means for preventing the biasing of the relays in response to voice waves, the repeater being at all times operative to conduct current in each direction to an appreciable extent. 5

6. In a telephone repeater for use with two-wire telephone lines, two separate amplifying elements with variable gain for transmission in the two directions, a voice-operated device associated with each amplifying element, a relay controlled thereby, each relay being adapted to increase the gain of the associated amplifying element and to make a corresponding decrease in the gain of the other amplifying element, means responsive to noise in either side of the circuit for biasing both the said relays to prevent operation thereof by the noise, means for preventing the biasing of the relays in response to voice waves, and means for preventing interaction between the two sides of the repeater due to the association therewith of the biasing means, the repeater being at all times operative to conduct current in each direction to an appreciable extent. 10 15
